UNITED STATES PATENT OFFICE

CLYDE L. HEISHMAN, OF WASHINGTON, DISTRICT OF COLUMBIA

ILLUMINATED BOARD

Application filed February 20, 1929. Serial No. 341,419.

This invention relates to illuminated structures, and is particularly useful as a stock broker's board and is so described, but is capable of use for other purposes, and no limitation in this respect is implied.

Brokers' offices commonly have a board in which are displayed, on the wall, quotations concerning stocks and other articles, adapted to be changed as prices vary, and so displayed that the prices can be seen by a considerable number of traders. With a great number of items, finding wall space becomes a matter of considerable difficulty, and one of the objects of the present invention is to relieve this condition.

Quotations on active stocks are best displayed where they can be seen at all times by a considerable number of traders, but with respect particularly to inactive stocks or items this condition is not demanded, and it is sufficient that the quotations be displayed in such manner as to be easily accessible to the few traders who are particularly interested in the inactive items, or to clerks who may desire to inspect the board for the prices of such items. Provision must be made however for changing the prices as the market changes. The present invention is designed therefore to provide a board for the indicated purposes, which can be used as an addition to the regular wall board, the items on which can accordingly be reduced by the removal of such as may be transferred to the present apparatus. However, the invention may be applied, with obvious changes, to a wall board, and in any event will serve the purpose of providing means for exhibiting quotations on many items, and capable of being easily changed as the market varies.

One form of the invention is illustrated in the accompanying drawings, and is herein-after described, and in the drawings Fig. 1 is a perspective view of the device, showing the front. Fig. 2 is a similar rear view. Fig. 3 is a perspective of one of the glass panels which forms the top or face of the board or structure. Fig. 4 is an enlarged section on the line 4—4 of Fig. 3. Fig. 5 is a perspective of one of the strips containing a list of stocks or other items, together with its backing strip.

Fig. 6 is a perspective of the structure with the glass top removed, and partly broken away. Fig. 7 is a detail in section of the top part of the structure. Fig. 8 is a section on the line 8—8 of Fig. 7. Fig. 9 is a complete vertical section showing the illuminating devices. Fig. 10 is a section on the line 10—10 of Fig. 9. Fig. 11 is an enlarged view of a section of the top. Fig. 12 is a detail in section of the inside of the casing.

As herein illustrated the structure comprises an elongated casing or counter which may be made of any suitable material, having a front 6, a back 7, ends 8, a bottom 9, and supported by legs 10. At the rear a shelf 11 is provided, convenient for supporting telephones, tickers and other articles, and under this is a trunk 12 for wiring or other purposes. Sliding drawers 13 may also be provided, if desired.

The top of the counter or structure consists of a series of glass panels 14, conveniently supported in an inclined position, to form a long "board" or surface to receive the quotations. This surface or top is illuminated from below, as by a number of lamps 15, such as electric bulbs mounted on the front and rear walls, under shields or shades 16. The inside of the counter or casing has a reflecting surface, which may be produced by a coat of white or light color paint, and the shields 16 are so constructed that the glass or top is protected from the direct rays of the light and is illuminated by reflected light, as indicated in Fig. 9. This gives a diffused and even illumination of the whole glass top.

The glass panels 14 rest at each end upon the front and rear walls of the casing, being preferably seated in rabbets therein, and they are also supported by cross bars 17 on which they rest, between the front and rear walls. Each bar 17 has a groove 18 along the top, and these grooves receive and hold the strips 19 on which the list of stocks or other items, and their abbreviations, may be typewritten or printed, preferably in alphabetical order throughout the various strips. Each strip has a somewhat rigid backing or filler strip 20, and the ends of the strip 19 project somewhat beyond the ends of the filler strip, so that

when the glass plates 14 are in place the projecting ends are clamped between the ends of the plates or panels and the rabbets in the front and rear walls in which said ends fit.

5 This arrangement causes the strips to be pressed closely against the under side of the glass panels, so that they can be easily seen and read.

Each panel 14 has a transparent part 22, of 10 clear glass, which is of proper width to fit over the corresponding strip 19, and adjacent said column 22 it has a series of columns 23 which are ground on the surface or otherwise made translucent and with such a sur-

15 face pencil marks may be made thereon, and erased when desired. These columns may represent "opening", "high", "low", and "closing" prices, and the columns are all arranged or provided with transverse rows to

20 align the prices marked thereon with the items appearing on the strips 19. The panels are preferably separately removable so that they can be lifted to permit access to the strips below, or to the interior of the casing. Holes

25 30 in the back wall 7 are vents for heated air.

It will be seen that a large number of items can be listed on the strips 19, to occupy very little space, and on a structure of moderate length several hundred or more items

30 can be displayed, together with the prices relating thereto.

In use, it is intended that board boys or clerks shall enter the quotations of the respective items in the columns 23 corresponding

35 thereto, and by erasing the same make such changes as are necessary, according to the market. The quotations so entered can be seen by interested persons, the figures standing out clearly because of the illumination from

40 below. The glass panels form a continuous glass top which can be easily kept clean and in condition for continuous use and such changes in the list or the quotations as may be necessary.

45 As stated the invention is illustrated in the form of a counter to stand on the floor, but the same idea could be embodied in a wall board having an illuminating compartment the front or exposed surface of which is provided 50 with the glass panels and the lists, or their equivalents.

The corner posts 31 of the structure, and the bars 17, are preferably beveled off or tapered as indicated at 32 to avoid objectionable 55 shadows or uneven illumination of the top.

I claim:

1. An illuminated structure comprising a casing containing lamps, spaced supporting bars extending across the casing, translucent plates mounted on said bars, and strips on the bars, the plates having transparent portions through which the strips can be seen.

60 2. An illuminated structure as in claim 1, the plates being marked into columns and into 65 rows.

3. An illuminated board for stock quotations, comprising a casing, means to illuminate the interior thereof, and a translucent wall on the casing, through which the light shines, said wall having columns, and rows marked thereon and illuminated by the light in the casing.

4. An illuminated quotation board for stocks, comprising a casing having a glass top and lamps within the casing, and means to support strips containing lists of stocks in columns under the top and visible through the same, the top having columns marked thereon.

5. An illuminated quotation board as in 80 claim 4, said means consisting of bars on which said strips are mounted, extending across under the top.

6. An illuminated price board comprising a casing, means to illuminate the interior 85 thereof, a glass top on the casing, and strips under the top containing lists of items, the top having transparent columns marked thereon corresponding to said lists and through which they may be seen, and translucent columns marked thereon beside said transparent columns on which translucent columns price marks may be made, in line with the corresponding items of the list.

7. An illuminated price board as in claim 90 6, the top being made of a series of separately removable panels permitting removal of the lists respectively.

8. An illuminated structure for exhibiting 95 prices, comprising a casing having a wall containing transparent and translucent columns marked thereon, means within the casing to illuminate said wall by reflected light, and means to support lists of items under the transparent columns.

9. An illuminated structure as in claim 8, the means to support said lists consisting of bars extending across behind the said wall, between which bars and wall the lists are confined.

10. An illuminated structure for exhibiting 100 prices, comprising an internally illuminated casing having a top with transparent and translucent columns marked thereon, grooved bars extending across the casing under said transparent columns, and strips containing lists of items in the grooves and visible through said transparent columns, the translucent column portions of the top being surfaced to receive marks.

11. An illuminated structure as in claim 10, the top being made of separately removable glass panels permitting removal of the strips respectively.

12. An illuminated board for stock quotations, comprising an internally illuminated casing having a glass face made of separately removable panels, bars extending across the casing behind said face, and strips supported 13

between said bars and the face, and containing lists of stock items, the face having transparent portions through which said lists are visible and translucent portions arranged in columns and in rows corresponding to the various items of the lists.

5 In testimony whereof, I affix my signature.
CLYDE L. HEISHMAN.
